RETURN BEND

Arthur H. Moorhead, Atchison, Kans., assignor
to The Locomotive Finished Material Company,
Atchison, Kans., a corporation of Kansas

Application January 24, 1934, Serial No. 708,056

5 Claims. (Cl. 137—76)

My invention relates to return bends for pipes and more particularly to return bends for use on high pressure tubular oil stills, or in similar structures in which a fluid under high pressure 5 is employed or treated.

In tubular oil stills the hot oil passing through the various banks of tubes causes a deposit of coke or carbon on the walls of the tubes which necessitates frequent cleaning of the tubes. It 10 is therefore necessary that proper access to the interiors of the various tubes be permitted without necessitating dismantling of the tubes or of the return bend itself.

Return bends of the type in question are generally of elongated or rectangular and hollow construction with one longitudinal wall provided with suitable openings arranged in predetermined and proper spaced relation lengthwise of the bend element, while the opposite longitudinal wall is 20 also provided with openings arranged directly opposite to the first mentioned openings and therefore in alignment with the tube-ends secured in the first mentioned openings. The second mentioned openings constitute the clean-out holes 25 and permit proper access to the tubes connected into the return bend member.

The second mentioned openings are provided with suitable closure members or plugs which have a tight sliding fit in the openings; and these 30 plugs therefore are held in place by suitable pressure applying elements generally in the nature of screw-bolts which are carried by and have adjustable relation with yokes or toggles.

My invention more specifically stated relates to 35 the construction and formation of elements whereby the yokes or toggles are firmly held in position to permit the screw-bolts to exert proper pressure on the closure member or plugs.

The invention has for its object the provision 40 of yoke or toggle holding means so arranged as to permit the tube centers and hence the centers of the tube receiving openings to be closer together, a condition extremely desirable in the industry.

45 A further object of the invention is to provide such toggle holding means formed integral with the header or return bend which will also constitute reenforcing members or ribs disposed diagonally across the top of the header or return bend.

The objects and advantages of my invention will be readily comprehended from the detailed description of the exemplifications of my invention as disclosed in the accompanying drawing, 50 wherein:

Figure 1 is a top plan view of a return bend without the closure members; with a part at the right being in section.

Figure 2 is a partial side elevation and longitudinal sectional view of the return bend shown 60 in Figure 1.

Figure 3 is a transverse sectional view of a portion of the return bend with a closure member and holding means in position; the section of the return bend being substantially on the line 3—3 65 of Figure 1.

Figure 4 is a top plan view, with a portion in section, showing a modified form.

In the particular exemplifications of the invention, the return element or bend 10 is illustrated 70 as applicable to four pipes or tubes and therefore the one longitudinal side wall is shown provided with four pipe or tube receiving openings 11; the openings being of size and construction in keeping with the size and nature of the tubes which 75 may be expanded into place.

As is apparent the fluid or oil coming from the end of one tube may freely flow into the end of an adjacent tube.

Where these return bends are employed in oil 80 stills, it is necessary to provide openings in direct alignment with the tube ends inserted in openings 11, to permit easy access to the tubes for the purpose of removing the coke or carbon, which forms during oil distillation and enable 85 the various tubes of the still to be cleaned. Therefore, the longitudinal wall opposite to the wall having openings 11 is likewise provided with openings 12 which are in concentric alignment with the openings 11. 90

The walls of the openings 12 are shown preferably tapered inwardly, see Figures 2 and 3, to receive tapered closure members or plugs 13, see Figure 3.

Oil stills are usually operated under relatively 95 high pressure and it is essential therefore to provide means for securely holding the closure members or plugs 13 in place.

This means, according to my invention, consists in providing the longitudinal side or wall 100 having openings 12 with integral and outwardly disposed lobes or posts 14, 14 at opposite ends of the return bend 10; and with the sinuous ribs 15, disposed intermediate of adjacent openings 12. 105

The lobes or posts 14 and the ends of the ribs 15 are intended to be arcuately disposed in close proximity to the openings 12 as shown in Figure 1.

As more clearly shown in Figure 1, the up-standing lobes or ears of two adjacent openings 110

12 are combined into a diagonally disposed rib 15 extending from one longitudinal side edge to the opposite longitudinal side edge; with the end portions of each rib 15, where they approach the 5 perimeters of adjacent openings 12, made arcuate. The arcuate end portions of each sinuous rib 15 are each provided with a suitable slot 16; the slot 16 in one rib 15 being diagonally in alignment with a slot 16 in the end of an adjacent 10 rib, see Figure 1.

The posts 14 at opposite ends of the return bend 10 are also disposed adjacent to the perimeters of the openings 12 at the ends of the return bend; and these posts are preferably also 15 made arcuate, thus, like the ends of the ribs 15, permitting them to be in close proximity to the openings without unduly enlarging the transverse dimensions or width of the return bend 10. The posts 14 are also each provided with a 20 slot 17, similar to the slots 16 and placed in diagonal alignment with the slots 16 in the ribs whose ends are adjacent the openings 12 at the ends of the return bend.

The slots 16 in the ribs and slots 17 in the 25 posts are intended to receive the wings or ends of a yoke or toggle as shown at 18 in Figure 3. These toggles 18 are of well known construction; the central portions being provided with tapped openings to receive the clamps or set-screws as 30 shown at 19 in Figure 3; the ends of the set-screws being made to engage the plugs 13 and firmly hold them in place against the pressure of the fluid.

Aside from the function of holding and providing purchase for the yokes or toggles, the ribs 35 15, by reason of their construction, also greatly reenforce the outer longitudinal wall of the return bend against any buckling or bending tendency.

40 In Figure 4 I illustrate a modified form of yoke or toggle holding means in the nature of a continuous serpentine rib 20, which extends from one end to the other of the header or return bend 10^a. That is to say, the rib 20 extends from one 45 longitudinal edge of the return bend, partially about the plug receiving opening, and to the other longitudinal edge, thus providing a continuous reenforcing rib extending from end to end which will prevent any possibility of bending 50 the header or return bend.

The arcuate portions of the rib 20 are also preferably arranged in close proximity to the perimeters of the plug receiving openings and these portions are provided with suitable slots 16.

55 The header on the sides of the plug receiving openings, which are not encircled by the serpentine rib 20, is provided with ears or posts 21 which are also preferably made arcuate and arranged in close proximity to the perimeters of the 60 openings.

65 These posts or ears 21 also have slots 17 like posts 14 and similar to the slots 16 in the rib and arranged diagonally opposite to the slots 16 in the rib, as shown in the drawing.

70 These slots, like those in the structure shown in Figures 1 and 2, are intended to receive the ends of suitable yokes or toggles which extend transversely of the openings, after the closure plugs 13 have been put into place, and provide support for the pressure applying screw-bolts.

The sinuous or serpentine types of ribs, as heretofore described, permits closer tube centers to be had, which is extremely desirable in the oil still industry and which was not possible with 75 return bends of this general type; while at the

same time the upper or outer side of the header or return bend is greatly reenforced against any bending possibility. The sinuous diagonally disposed and serpentine types of reenforcing ribs permit the manufacture of lighter headers or return bends than heretofore has been possible and yet possessing the necessary strength; a decided advantage where the headers must be handled in the erection of large banks of tubes.

80 In box type return bends, as heretofore employed, the toggle holding posts or mule ear projections were so located that the toggles would be disposed at right angles to the length of the bend or fitting. The width of the mule ears necessary to provide the required strength limited 85 the minimum distance between tube centers possible to be used. Whereas, with my improved design of combining two or more mule ears disposed adjacent opposite sides of the header and forming one or more cross-ribs on the top or 90 outer face of the fitting, makes it possible to reduce the distance between the tube centers, a decided advantage in the refining industry and to 95 produce a lighter and more compact fitting.

100 Shortening the distance between the tube centers enables the return bend to be made shorter and hence provides a saving in return bend lengths which is greatly desired particularly where large banks of tubes are employed.

105 In describing the specific exemplifications of the invention, terms have been used for purposes of description and not as terms of limitation as modifications are possible and may be made without, however, departing from the spirit of my invention.

110 What I claim is:

115 1. A return bend comprising a hollow member, the opposite longitudinal sides whereof are provided with a plurality of aligned openings, the openings in one side being tube end receiving 120 openings while those in the opposite side are clean out and closure-plug receiving openings, and yoke or toggle holding means disposed transversely of the hollow member and extending between the perimeters of the openings and the adjacent edges of said member.

125 2. A return bend comprising a hollow member, two opposite longitudinal sides whereof are provided with openings, one of said longitudinal sides being provided with integral outwardly disposed toggle holding elements, a part of said elements being in the form of a continuous rib extending in serpentine manner substantially from one end of the member to the other intermediate of the perimeters of the openings and the longitudinal edges of the member, the other part of said elements being in the form of ears or 130 posts disposed adjacent to the openings at points diametrically opposite to the arcuate portions of the serpentine rib; said arcuate portions of the serpentine rib and said posts being provided with toggle holding surfaces.

135 3. A return bend comprising a hollow member, two opposite longitudinal sides whereof are provided with openings, the openings in one side being provided with removable plugs, screw-bolt carrying toggles for maintaining the plugs in place, and toggle holding means formed integral with said longitudinal side of the member, a portion of said means extending between the perimeter of one opening and one longitudinal edge of the member, across said longitudinal side and thence between the perimeter of an adjacent opening and the other longitudinal edge of the member, the other portion of said means being 140 145 150

disposed adjacent to the openings diametrically opposite to said first mentioned portion, both portions at points diametrically opposite each other being provided with toggle holding surfaces.

5 4. A return bend comprising a hollow member, one longitudinal side whereof is provided with a plurality of clean-out openings, closure plugs for said openings, plug pressure applying elements, and means formed integral with said member and 10 adapted to hold said pressure applying elements, a portion of said means extending sinuously from one longitudinal edge of the member to the opposite longitudinal edge and in proximity to a plurality of said openings whereby the member 15 is reenforced transversely and longitudinally.

5. A return bend comprising a hollow member,

one longitudinal side whereof is provided with a plurality of uniformly spaced openings, closure plugs for said openings, plug pressure applying elements, and means formed integral with said longitudinal side and adapted to hold said pressure applying elements, a portion of said means extending sinuously from one longitudinal edge of the member to the opposite longitudinal edge and about a portion of the perimeters of the respective openings, a second portion being disposed adjacent the other portion of the perimeters of the openings, both portions of said means being provided with slots adapted to receive said elements and to hold the same transversely of the openings.
